UNITED STATES PATENT OFFICE.

SYDNEY E. LEE, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A GRILLE FOR RADIOAMPLIFIER.

Application filed August 13, 1926. Serial No. 18,731. Term of patent 7 years.

To all whom it may concern:

Be it known that I, SYDNEY E. LEE, a citizen of the United States, residing in the city of Chicago, in the county of Cook and the State of Illinois, have invented a new, original, and ornamental Design for Grille for Radio Amplifier, of which the following is a specification, reference being had to the accompanying drawings, forming a part thereof.

In the drawings:

Figure 1 is a front face view of a grille embodying my new design.

Figure 2 is a transverse section taken substantially as indicated at line, 2—2, on Figure 1.

I claim:—

The ornamental design for a grille for radio amplifier, substantially as shown.

In testimony whereof, I have hereunto set my hand this 2nd day of August, 1926.

SYDNEY E. LEE.
